(57) **CLAIM**

The ornamental design for a packaging bag, as shown and described.

DESCRIPTION

1. Packaging bag

1.1 : Front

1.2 : Top

1.3 : Right

1.4 : Bottom

1.5 : Back

1.6 : Perspective

1.7 : Folding state in use

In the reproductions, the broken lines are for illustrative purposes only and form no part of the claimed design; the dot-dashed thin lines in reproductions 1.1 and 1.7 illustrate a boundary between the claimed portion and the unclaimed portion and form no part of the claimed design; the long dash, short space thick lines and the thick solid lines in reproduction 1.1 represent guidelines for folding and are parts of the claimed design; reproduction 1.7 shows a folding state in use of the packaging bag.
